UNITED STATES PATENT OFFICE.

EDWARD J. JUDGE, OF SAN FRANCISCO, CALIFORNIA.

CAN-CAPPING MACHINE.

No. 869,091.

Specification of Letters Patent.

Patented Oct. 22, 1907

Application filed February 2, 1907. Serial No. 355,362.

To all whom it may concern:

Be it known that I, EDWARD J. JUDGE, of the city of San Francisco, in the county of San Francisco and State of California, have invented certain Improvements in 5 Can-Capping Machines, of which the following is a specification.

In the description of the said invention which follows, reference is made to the accompanying drawings forming a part hereof, and in which,—

10 Figure 1 is a partly sectional side view of the improved machine, and Fig. 2 a partly sectional plan of the same. Fig. 3 is an enlarged section of Fig. 1 taken on the dotted line $x-x$. Fig. 4 is an enlarged section of Fig. 1 taken on the dotted line $y-y$. Fig. 5 is an 15 enlarged sectional view of the burner shown in section in Fig. 1. Fig. 6 is an enlarged exterior side view of a receptacle for soldering fluid shown in Fig. 1, and Fig. 7 an enlarged top view of the same. Fig. 8 is an enlarged vertical section of the devices whereby soldering fluid 20 is directly applied to the crease in the can top prior to the soldering operation.

Referring now to the drawing, 1 is a table supported by the legs a .

2 is a circular carrier for the cans to be capped, secured 25 to a shaft 3 which is adapted for rotation in a bearing b formed as a part of the table 1. The cans are represented by X .

3, 4 are can supports, shown as twelve in number, consisting of disks fastened to the upper ends of stems c 30 adapted to have a rotary as well as a vertical reciprocating movement in the circular carrier 2, produced as hereinafter described.

5, 5 are spur pinions made tight on the stems c and adapted to mesh with teeth on the periphery of a fixed 35 circular plate 7 (see Fig. 1) which is fastened to the hub of the stationary table 1.

9 is an elevated frame on the rotary central shaft 3 which is provided with a feather whereby the frame will have a rotary movement in common with the circular carrier 2, and is supported by a threaded sleeve 11 40 for purposes of vertical adjustment. The office of the frame 9 is to carry the burners 10 which effect the soldering of the caps to the cans, together with the appliances hereinafter described, which introduce gas, and air 45 under pressure at proper times to the burners to produce soldering flames. The said burners (see Fig. 5) have each an annular chamber 12 for mixed air and gas, and a multiplicity of minute holes d from which flames issue.

50 13 is a head fastened to the upper end of the hub of the frame 9, which is centrally bored to receive the stationary air cylinder 14, and the gas cylinder 15 which is screwed tightly into the lower end of the air cylinder and closed at the bottom. The air cylinder 14 has a 55 nozzle e to receive the end of the pipe 17 which leads to a source of supply (not shown) of air under pressure:

and it is prevented from withdrawal from the head by means of a collar f which is held to the head by means of screws not shown.

19 is a fixed or stationary gas pipe the lower end of which is turned to fit closely in the upper end of the gas cylinder 15; and the said pipe being smaller than the inner diameter of the air cylinder, there is formed an annular passage g which is in communication with the radial air ducts h into which are screwed the air pipes 60 65 20.

Referring particularly to Fig. 5 it will be seen that at the lower end of each air pipe 20 is a tee j connected at one end by means of a nipple k to the air chamber 12 of a burner 10; and that the other end of the tee is united 70 by a gas pipe 21 to a duct m leading to the interior of the gas cylinder 15. The portion of the gas pipe 21 within the tee is made tapered to give a space around it for the passage of compressed air which, during certain periods of the operation of the machine mixes with the gas 75 entering the burner.

It is intended that neither the compressed air, nor the gas shall pass continuously to the burners, but instead, intermittently; that the flame produced by combined gas and compressed air shall play upon the cans during 80 a portion only of their revolution around the axis of the central shaft 3; and that after the flow of gas is cut off the air shall continue to blow on the soldered joints to cool them.

To effect the results just described, the slot n in the 85 wall of the gas cylinder, which serves as means of communication between the interior of the said cylinder and the pipes 21, is much shorter than the slot o in the wall of the air cylinder which has a similar function with respect to the said cylinder and the pipes 20; and 90 the two slots are relatively placed so that in the rotation of the head in the direction indicated by the arrows in Figs. 3 and 4, gas is admitted to a pipe 21 as it reaches the position denoted by A and is constantly supplied with gas until it passes the position B when the flow of 95 gas is cut off. Compressed air enters a pipe soon after it passes the position A, and the supply is continued until the pipe reaches the position C in Fig. 3. The slot n is indicated in Fig. 3 by the dotted radial lines.

It is necessary that gas should be admitted to burners in advance of the compressed air, in order that it may be ignited; and ignition is effected by the constant flame 23 illustrated in Fig. 2.

25 represents the driving shaft of the machine from which movement is communicated to the intermediate 100 vertical shaft 27 through the medium of the beveled gear wheels 29 and 30; and rotary motion is transmitted from the said vertical shaft to the central shaft 3 by means of the pinion 31 and the gear wheel 32.

It is desirable to feed the cans to be capped to the 110 can supports 4 by mechanical means, and to this end, a bracket 33 (see Figs. 1 and 2) is extended horizontally

from two of the legs *a* and provided at its end with a fixed or stationary table 35.

Centrally of the table 35 is a vertical shaft 37 which is rotated from the central shaft 3 by means of the

5 sprocket wheels 39 and 40 of a common diameter, and a sprocket chain 41. To the shaft 37 is fastened a disk 43 having can pockets *p* therein.

44 is an endless conveyer belt (see Figs. 1 and 2) the upper lay of which passes between the table 35 and 10 the disk 43 above it, as shown in Fig. 1.

45 is a deflector which switches uncapped cans from the endless conveyer belt 44 to the pockets *p* in the disk 43 and guides them while seated on the table 35 to the can supports 4; and 47 a second deflector to return 15 the cans to the pocketed disk and the table 35 after the capping operation. A third deflector 49 serves to remove the capped cans from the pocketed disk and the table 35 and return them to the conveyer belt which discharges them to some convenient point.

20 The formation and length of the deflector 45, and the distance of the circumference of the pocketed disk from the line described by the axes of the cans in their rotation around the central shaft are such that cans of a certain diameter are placed vertically of the can supports as shown in Fig. 2.

25 50, 50 are weighted cap holders (see Fig. 5) adapted to have an up-and-down movement in the frame 9, and extend downward through and centrally of the annular burners 10, and they are provided with loose ends 30 *q* which rotate with the cans in the capping operation.

35 51 is a cam ring fastened to the upper surface of the table 1, and situated under the fixed toothed plate 7 upon which rest the ends of the stems *c* of the can supports 4. The height of the cam ring 51 above the table 1 for a circumferential distance indicated by the dotted line between C and A in Fig. 2, is such that the upper surface of the can supports directly over it are flush with the table 35, while the remainder of the ring is considerably higher. The stems of the supports upon 40 reaching the higher portion of the cam ring, cause the supports to rise and bring the cans seated upon them into contact with the weighted holders which hold the cap in place.

45 52 is a vessel containing soldering fluid, attached to one end of a lever 54 loosely fulcrumed to the upper end of the shaft 37, and prevented from rotating with the shaft by means of an arm 53 the base *r* of which is fastened to the deflectors 45 and 47, as shown in Fig. 2.

50 55 is a bar extending from the lever 54 with its end resting on the disk 43 which has twelve projections *s* arranged in a circle as shown in Figs. 1 and 2 and which in the rotation of the disk successively lift the rod and cause the vessel 52 to descend.

55 56 is a siphonic pipe leading from the vessel 52 to a position directly over the can which has just entered a pocket in the disk 43 as shown in Fig. 2, and at the end of the pipe is a valve chamber 57 which receives soldering fluid from the vessel 52.

60 Into the lower head of the chamber 57 is screwed a pipe *t* having the annular hollow head 59 at its end. The discharge from the annular head is by means of minute holes *w*. The stem *v* of the valve 60 in the chamber 57 projects below the head 59, and as the lever 54 is tripped by the projections *s* on the pocketed 65 disk 43 as before stated, and the vessel 52 lowered, the

stem *v* strikes the center of the can cap and the valve is momentarily opened which causes a small quantity of the soldering fluid to be discharged to the crease of the can.

61 is a pipe leading from the interior of the vessel 52 70 to a source of compressed air to aid in the discharge of the soldering fluid in the manner before described, and 62 a check valve in the said pipe to prevent the soldering fluid from being forced up the pipe 61 should that pipe be disconnected from the compressed air 75 tank.

The machine being in motion, the operation of cap- 80 ping cans consists as follows: A can provided with a cap which may have been previously treated at its edges with solder, is placed on the endless feed belt 44 by

which it is carried towards the table 35 and the disk 43, and upon reaching them is switched by the deflector 45 into one of the pockets *p* in the disk, when soldering fluid is applied to the cap in the manner before described. It is then carried around on the table 35, 85 still in contact with the deflector, until it reaches one of the can supports upon which it is pushed, and centered thereon by the joint action of the deflector and the circumference of the disk 43, as shown in Fig. 2. The can then begins its revolution around the central 90 shaft, and when nearing the position A is lifted until its cap is pressed into contact with the weighted cap holder; and upon the can reaching position A, gas is turned on which is immediately ignited from the flame 23. Upon a slight further forward movement of the 95 can, compressed air is admitted to and mingled with the gas in the burner and an intensely hot flame produced which plays upon the caps until the can reaches position B when the flame is extinguished by the stoppage of the gas supply. The flow of compressed air 100 however, is not stopped and serves to cool the can until the can reaches position C when the can is switched again to the table 35 and into a pocket in the disk 43 by means of the deflector 47 and discharged through the medium of the deflector 49 to the endless belt 44 105 which carries it away from the machine.

I claim as my invention:—

1. In a can-capping machine, a rotary table provided with a system of can supports, combined with burners situated over the can supports, and apparatus to intermittently effect the production and extinction of a flame at the burners during their revolution about the axis of the table, substantially as specified.

2. In a can-capping machine, a rotary table, a system of can supports on the table with means to effect their axial rotation during the rotation of the table, combined with burners which are placed over the said supports and move in common therewith, and apparatus to effect the intermittent production and extinction of a flame at the burners during their revolution around the axis of the table, substantially as specified.

3. In a can-capping machine, a rotary table, a system of can supports on the table with means to effect the rotation of the table, and mechanism to produce in the can supports a vertical reciprocating movement, combined with burners which are placed directly over the said can supports and are revolved in common therewith, apparatus to intermittently admit gas to the burners, and other apparatus to intermittently admit compressed air to the burners independently of that which supplies the gas, and means to ignite the gas at the burners before the admission of air thereto, substantially as specified.

4. In a can-capping machine, a rotary table, a system of can supports on the table with means to effect their axial rotation during their revolution about the axis of the 135

table, and mechanism to produce in the can supports a vertical reciprocating movement, combined with burners which are placed over the said supports and are revolved in common therewith, and apparatus to effect the intermittent production and extinction of a flame at the burners during their revolution, substantially as specified.

5. In a can-capping machine, a rotary table, a system of can supports on the table with means to effect their axial rotation during their revolution about the axis of the table, and mechanism to produce in the can supports a vertical reciprocating movement, combined with burners which are placed directly over the said supports and are revolved in common therewith, apparatus to intermittently admit gas to the burners, and other apparatus to admit compressed air to burners independently of that which supplies the gas, and means to ignite the gas at the burners before the admission of air thereto, substantially as specified.

6. In a can-capping machine, a rotary table, a system of can supports on the table with means to effect their movement in common with the table, burners placed over the can supports and apparatus whereby gas is admitted to the burners and ignited, air forced into the gas before it reaches the burner, the flow of gas cut off and the air blast discontinued, the whole of the said operation being performed during one rotation of the table, substantially as specified.

7. In a can-capping machine, a rotary table carrying can supports, combined with a rotary disk having pockets, an endless conveyer belt upon which cans are placed, a deflector to switch the cans from the conveyer belt to pockets in the said disk and push them from the pockets to the can supports, and means to return the cans from the said can supports to the pocketed disk and thence to the conveyer belt, substantially as specified. 30

8. In a can-capping machine, a rotary table carrying can supports, a conveyer belt on which the uncapped cans are placed, and a pocketed disk to remove the cans from the conveyer belt and transfer them to the can supports, combined with apparatus to apply soldering fluid to the cans while the same are within the pockets of the disk, substantially as specified. 35

9. In a can-capping machine, a rotary table carrying can supports, a conveyer belt on which the uncapped cans are placed, and a pocketed disk to remove the cans from the conveyer belt and transfer them to the can supports, combined with apparatus to apply soldering fluid to the cans before the same are seated on the said supports, substantially as specified. 40 45
